UNITED STATES PATENT OFFICE

139,665

DESIGN FOR A TAPE DISPENSER UNIT

Milton Kahn, New York, N. Y., assignor to The Cofax Corporation, Long Island City, N. Y., a corporation of New York

Application October 14, 1944, Serial No. 115,788

Term of patent 14 years

(Cl. D74—1)

To all whom it may concern:

Be it known that I, Milton Kahn, a citizen of the United States and residing at New York, in the county of New York and State of New York, have invented a new, original, and ornamental Design for a Tape Dispenser Unit, of which the following is a specification, reference being had to the accompanying drawing, forming part thereof, and in which

Fig. 1 is a top plan view of the tape dispenser unit showing my new design.

Fig. 2 is a front elevation, and

Fig. 3 is a rear elevation.

I claim:

The ornamental design for a tape dispenser unit, substantially as shown.

MILTON KAHN.
